(57) **CLAIM**

The ornamental design for a “back brace with heating and vibration,” as shown and described.

DESCRIPTION

FIG. 1 is a front perspective view of an embodiment of the present design with the back brace configured with overlapped ends.

FIG. 2 is a rear perspective view of the embodiment of the present design with the back brace configured with overlapped ends.

FIG. 3 is a front perspective view of the embodiment of the present design with the back brace in a flattened configuration

FIG. 4 is a rear perspective view of the embodiment of the present design with the back brace in the flattened configuration of FIG. 3.

FIG. 5 is a front elevation view of the embodiment of the present design with the back brace in the flattened configuration of FIG. 3.

FIG. 6 is a rear elevation view of the embodiment of the present design with the back brace in the flattened configuration of FIG. 3.

FIG. 7 is a top plan view of the embodiment of the present design with the back brace in the flattened configuration of FIG. 3.

FIG. 8 is a bottom plan view of the embodiment of the present design with the back brace in the flattened configuration of FIG. 3.

FIG. 9 is a left side elevation view of the embodiment of the present design with the back brace in the flattened configuration of FIG. 3; and,

FIG. 10 is a right side elevation view of the embodiment of the present design with the back brace in the flattened configuration of FIG. 3.

In FIGS. 1-10, broken lines are shown to define boundaries around portions of the article which are not part of the claimed design.

1 Claim, 6 Drawing Sheets
